UNITED STATES PATENT OFFICE.

GEORGE CULTON, CHARLES ABLETT, AND WILLIAM EDWARD LIGHTFOOT, OF
LIVERPOOL, ENGLAND.

SPEED-REGULATING DEVICE FOR SOUND RECORDING AND REPRODUCING MACHINES

964,684.

Specification of Letters Patent, Patented July 19, 1910.

Application filed February 23, 1909. Serial No. 479,670.

To all whom it may concern:

Be it known that we, GEORGE OULTON, CHARLES ABLETT, and WILLIAM EDWARD LIGHTFOOT, subjects of the King of Great Britain and Ireland, residing at Liverpool, in the county of Lancaster, England, have invented new and useful Improvements in Speed-Regulating Devices for Sound Recording and Reproducing Machines, of

10 which the following is a specification.

This invention relates to sound recording and reproducing machines employing disk records and particularly to such machines in which the speed of the motor can be continuously varied so that the relative linear speed between the record line and the stylus remains constant, or otherwise stated, the angular speed of the motor increases or decreases according to whether the record 20 commences at the periphery or near to the center of rotation.

The object of this invention is to obtain the differential speed of the motor in a simple and efficient manner and dispense 25 with any connection between the sound box or carrier thereof and the speed controlling device, providing means at the same time for indicating the proper position of the speed controlling device for records of different diameters.

The invention also provides that the motor can be run at a constant speed so that the ordinary or standard disk records can be used at will.

Hitherto the speed of motors in recording and reproducing machines, has been controlled by a cam actuated by or with the sound box carrier, the cam bearing against the brake lever so as to constantly vary its 35 position, the sound box carrier in some cases being traversed or guided solely by the spiral record groove or line through the stylus and in other cases a screw and nut being used to traverse the said carrier and 40 cam together, the latter moving across the brake lever in contact therewith. In these two cases it is obvious that the sound box carrier being connected directly or indirectly to the speed changing device, the correct 45 starting speed would synchronize with the position of the stylus on the record disk.

According to our invention, the sound box arm or carrier is quite independent of the speed controlling device, and we employ a 50 graduated scale and pointer to indicate the

proper starting speed for different sized records.

The drawing attached hereunto, illustrates our invention applied to the ordinary speed controlling device used in sound recording and reproducing machines.

In Figure 1 is represented an end elevation of the mechanism. Fig. 2 represents a plan of the same looking from underneath. Fig. 3 represents a side elevation omitting some of the parts for clearness' sake.

Referring to the several views, 1 represents the motor shaft, 2 the base plate of the mechanism, 3 the turntable or fast motion shaft, 4 the centrifugal speed controlling device and 5 the brake lever. The brake arm 7 of the brake lever, carrying the leather or like brake shoe 8 is fixed to a spindle 9 centered between the base 2 and a bracket 10. The other arm 11 of the brake lever, 75 is in the case illustrated approximately at right angles to the arm 7. A slideway consisting of a rod 12 fixed at one end in the bracket 13 is arranged alongside the arm 11 and upon this rod is a slide piece 14 carried 80 at the end of a tubular rod 15 into which the rod 12 telescopes. A handle such as a milled disk 16 is fixed at the end of the rod 15 for the purpose of drawing it in and out and turning it partly round. When the 85 motor is working, the brake disk 16 is drawn toward the brake arm 7 by the centrifugal action of the governor and keeps the arm 11 pressed against the slide piece 14. The inside face 17 of the arm 11 is approximately 90 straight and when the nose 18 of the slide piece 14 is in contact with the arm toward its lower end as seen in Fig. 2, the said face 17 lies at an angle in relation to the slideway so that as the slidepiece is drawn out 95 the end of the arm 11 approaches the slideway and the brake shoe 8 recedes before the governor disk 16. By this means, the motor can be set to run at any constant speed in the usual way by fixing the position of 100 the brake arm to accord with the desired speed, through the slide piece 14. The brake may also act as a stop when the slide piece is pushed right down, by pressing hard upon the disk 16 when in its uppermost position. In 105 order to automatically vary the speed of the shaft 3 as the motor is running down, by means of the above described device, a fine pitched screw 19 is mounted in bearings in the brackets 13 and 20, parallel with the 110

slideway 12. This screw is turned continuously by the motor through the pinion 21 gearing with one of the wheels 22 of the motor. The slidepiece 14 is provided with a pivoted arm 23 formed with a half nut 24 at its end, adapted to engage with the screw as shown, and by turning the milled disk 16, to be disengaged therewith. The finger 25 acts as a stop to the further turning of the slide piece when the nut is disengaged. The nose 18 of the slide piece is in the form of an arc as shown in Fig. 1, so that it remains in contact with the arm 11 when the milled disk 16 is turned either way.

15 A convenient form of indicator for setting the position of the slide piece in relation to the brake lever so that the correct starting speed can be obtained is shown in Fig. 3. The rod 15 is marked with a scale 20 26 representing the different diameters of records, and a pointer 27 is shown fixed to the base 1.

By disengaging the nut from the screw and pushing the rod 15 inward to its full extent, the slide piece 14 forces the arm 11 away from the slideway and thereby jams the brake on the disk 16 preventing the motor from working. By drawing the slide piece out the nut being still disengaged, the 30 motor will run at a speed in accordance with the sensitiveness of the governor and varying with the position of the slide piece in relation to the fulcrum of the lever, in the manner generally used. By turning the 35 rod 15 partly around and thereby engaging the nut with the screw, the latter revolving at a definite rate carries the slide piece along with it toward the fulcrum of the brake lever, assuming the nut was engaged toward 40 the end of the arm 11, thereby causing the brake shoe 8 to gradually recede from the brake disk when at rest, at a definite rate and controlling the brake pressure applied through the centrifugal action of the governor.

45 Provision is made for the nut to run off the threads of the screw by the clearance space 28.

What we claim as our invention and desire to secure by Letters Patent of the United States is:—

50 1. In machines for recording and reproducing sounds, in which disk records are employed, the combination with a motor 55 having a centrifugal frictional speed governor with a pivoted brake lever, of a slideable piece traversed by the motor along a slideway, an extending rod with handle and disengaging means to set the slideable piece 60 at any part of the slideway, an indicator to show the position of the slideable piece on the slideway, an arm on the brake lever in a plane parallel with the slideway, and means on the slideable piece and in connection with 65 said arm so that as the slideable piece is moved

the brake lever is rocked on its pivot for the purpose herein set forth.

2. In machines for recording and reproducing sounds, in which disk records are employed, the combination with a motor 70 having a centrifugal frictional speed governor with a pivoted brake lever, of an arm fixed to the brake lever and having a straight edge, a slideway alongside said arm and in a plane parallel therewith, a slide piece on 75 said slideway and having a sectoral face to bear against the straight edge of said arm, said slide piece being adapted to turn angularly on said slideway, a screw geared to the motor so as to turn therewith and parallel 80 with the slideway, a half nut fixed to said slide piece and adapted to engage with or be disengaged from the screw when the slide piece is turned, an extending rod fixed to the slide piece and provided with a handle so 85 that it can be turned or drawn in or out at will, and an indicator and scale for showing the longitudinal and engaging position of the slide piece and nut on the slideway for the purpose herein set forth.

90 3. In machines for recording and reproducing sounds, in which disk records are employed, the combination with a motor having a frictional centrifugal speed governor with a pivoted brake lever, of a straight arm 95 fixed to the brake lever, a round rod fixed alongside the said arm in a parallel plane, a screw geared to the motor so as to continuously rotate, and mounted in bearings so as to lie parallel with the said rod, a tube telescoped on said rod and having a handle at its outer end and a sectoral projection at its inner end adapted to bear against the straight side of the said arm of the brake lever and remain in contact while being 100 turned around, a stop to limit the angular movement of said tube, a half nut carried at the end of an arm fixed to the tube and adapted to engage with and disengage from said screw when the tube is turned, a stationary pointer, and a scale marking on the said tube adapted to correspond with different positions of sectoral projection, substantially as described and for the purpose herein set forth.

110 4. A speed regulating device for sound recording and reproducing machines comprising in combination, a governor for the machine provided with a braking member, a constant speed threaded rod operated by the 115 machine, and a longitudinally and rotatively adjustable indicating member provided with a nut engaging said rod and a portion engaging said member for automatically and gradually reducing or increasing the speed of said machine.

5. A speed regulating device for sound recording and reproducing machines comprising in combination, a governor for the machine provided with a braking member, a 120

- constant speed threaded rod operated by the machine, a longitudinally and rotatively adjustable graduated indicating member provided with a nut engaging said rod and a portion engaging said member for automatically and gradually reducing or increasing the speed of said machine, and a pointer projecting abreast of the graduation on said indicating member.
6. A speed regulating device for sound recording and reproducing machines comprising in combination, a governor for the machine provided with a braking member, a constant speed threaded rod operated by the machine, and a longitudinally and rotatively adjustable indicating member provided with a nut engaging said rod and an arcuate portion engaging said member for automatically and gradually reducing or increasing the speed of said machine, said arcuate member serving to maintain engagement with said braking member when said nut is out of engagement with said rod.
7. A speed regulating device for sound recording and reproducing machines comprising in combination, a governor for the machine provided with a braking member having an extension, a constant speed threaded rod operated by the machine, and a longitudinally and rotatively adjustable indicating member provided with a nut engaging said
- rod and a portion engaging said member for automatically and gradually reducing or increasing the speed of said machine, and a mounting for said indicator member for 35 guiding the same abreast of said extension.
8. A speed regulating device for sound recording and reproducing machines comprising in combination, a governor for the machine provided with a braking member, a 40 constant speed threaded element, and a longitudinally and rotatively adjustable and movable indicating member having a portion engaging said braking member and a nut engaging said element, said indicating 45 member when adjusted to disengage the nut from said element being adapted for longitudinal adjustment to stop the motor, allow it to run free under the governor, or retard the speed to a fixed rate, and serving when 50 adjusted to engage the nut with said element to automatically increase or decrease the speed of the machine.

In testimony whereof we have signed our names in the presence of two subscribing 55 witnesses.
